APPARATUS FOR ADMINISTERING
ANESTHESIA

Emil Einar Wilhelm Anderson, Lidingo, Sweden,
assignor to Svenska Aktiebolaget Gassac-
cumulator, Stockholm, Sweden, a corporation of
Sweden

Application May 26, 1938, Serial No. 210,120
In Sweden May 31, 1937

13 Claims. (CL 128—188)

My invention relates to apparatus for administering a gaseous anesthetic, such as nitrous oxide, and especially to an apparatus particularly adapted for administering an anesthetic for the relief of labor pains. For relieving labor pains it is desirable to maintain a weak narcosis, or so-called analgesic state, without permitting the patient to reach the excitation state or the absolute narcotic state. In the analgesic state the sensation of pain is removed, whereas the senses and the organs of the body are otherwise practically unaffected by the anesthesia. Most important, there is practically no decrease in the functions of the muscles.

In order to produce a short analgesic state it is necessary to administer a limited quantity of anesthetic. Heretofore this has been done by a physician or trained nurse and consequently it requires the constant attendance of such a person. Inasmuch as labor may continue for several hours, or in extreme cases for several days, it has been necessary for the physician, or nurse, to remain in attendance for such lengths of time.

One of the objects of my invention is to provide an apparatus which may be adjusted by the physician so as to administer a predetermined quantity of anesthetic, but which apparatus is under the control of the patient to the extent that she may determine when the anesthetic is to be administered. Thus, at the beginning of each labor pain, the patient is able to obtain a limited and predetermined amount of anesthetic which is sufficient to relieve the pain, but which is insufficient to produce an absolute narcotic state. Thereafter no more anesthetic may be obtained by the patient until a predetermined minimum period of time has elapsed.

A further object of my invention is to provide, in an apparatus of this type, means whereby the physician or nurse may administer, in an emergency, larger quantities of anesthetic.

Further objects and advantages of my invention will be apparent from the following description considered in connection with the accompanying drawings, which form a part of this specification, and of which:

Fig. 1 is a more or less diagrammatic cross-sectional view of one embodiment of my invention;

Fig. 2 is a similar view of a second embodiment of my invention; and

Fig. 3 is a similar view of a third embodiment of my invention.

Referring more particularly to Fig. 1, reference character 10 designates a container for a gaseous

anesthetic under pressure. Container 10 is provided with a valve 11 for controlling flow therefrom into a conduit 12 which is provided with a pressure gauge 13. Conduit 12 communicates with a pressure governor 14. Governor 14 consists of a casing 15 within which is mounted a diaphragm 16, the upper surface of which is subjected to atmospheric pressure through openings 17 in the cover of the casing. A spring 18 is mounted within the casing and is arranged to press against a bolt 19 carried by diaphragm 16. Bolt 19 engages an angular member 20 which is pivoted on a fulcrum 21 carried by the casing. Pivottally engaging member 20 is a valve stem 22 which is held in contact with member 20 by 15 means of a spring 23. Valve stem 22 carries a valve member which cooperates with a seat formed in a nipple 24 which is secured in the inlet passage 25 to which conduit 12 is connected. A plate spring 26 is stressed between the casing and 20 one end of angular member 20. Casing 15 is provided with an outlet opening 27 which is connected to a conduit 28.

The wall of casing 15 is provided with a bypass channel 29 which communicates with the inlet opening 25 ahead of nipple 24. A valve 30 is arranged to control flow between passage 29 and a chamber 31 to which is connected a conduit 32. Valve 30 is mounted on a stem 33 which extends outside of the casing and is provided with a button 34. A spring 35 tends to hold valve 30 in closed position.

Conduit 28 communicates with an adjustable throttle valve of suitable type. As shown, this valve includes a needle 37 formed with screw threads which engage similar threads in the casing and which may be adjusted with relation to a valve seat 38 so as to control flow through the valve.

A conduit 39 connects the outlet side of valve 36 with a valve chamber 40 formed in a casing 41. Conduit 32 also communicates with chamber 40. Mounted within the casing is a diaphragm 42, one side of which is subjected to atmospheric pressure through an opening 43 formed in the cover 44 of the casing. Rigidly connected to the center of the diaphragm by means of an arm 45 is a member 46 which is pivoted at 47 to the casing. Member 46 carries a valve 48 disposed in valve chamber 40 and a valve 49 arranged to control communication between the interior of diaphragm chamber 50 and a chamber 51. Member 46 is made of magnetic material and its end opposite from valves 48 and 49 55

is arranged to move between the poles 52 and 53 of a permanent magnet 54.

A spring-loaded valve 55 regulates communication between chamber 51 and a space 56 which is connected by means of a flexible tube 57 with an inhalation mask 58. A spring-loaded valve 59 regulates communication between space 56 and the atmosphere. The loading of valve 59 with respect to that of valve 55 is such that valve 10 55 opens under the influence of a smaller pressure differential than does valve 59.

Connected to diaphragm chamber 58 is an expandible bulb 60 made of rubber or other suitable material. Expansion of the bulb is limited 15 by means of plates 61 and 62, of which the former is fixed while the position of the latter may be adjusted by means of a set screw 63.

The above described apparatus operates as follows:

- 20 Gas under pressure is supplied from container 18 through valve 11 to conduit 12 and to the pressure regulator 14. The construction of this regulator is such that it maintains a constant pressure within the casing 15. If the pressure 25 within the casing tends to rise, it moves the diaphragm upwardly against the force of spring 18 and against the force of atmospheric pressure. This causes the angular member 20 to pivot in a counterclockwise direction about fulcrum 21 which forces valve stem 22 to the right against the force of springs 23 and 26, thus restricting the opening through nipple 24 and hence reducing flow of gas into the chamber. A drop in pressure within the chamber causes the 35 diaphragm to move in the opposite direction and thus increases the opening. The pressure regulator is adjusted to maintain a desired pressure, for instance, in the neighborhood of 5 mm. of water.
- 40 The gas under this pressure leaves the regulator through conduit 28 and passes through throttle valve 36, which may be adjusted to regulate the velocity of flow of gas therethrough.

When the apparatus is first started, atmospheric pressure acting on diaphragm 42 holds it in a position opposite to that shown in Fig. 1; that is, with valve 48 opened and valve 49 closed and with the lower end of member 46 in contact with the pole 53 of the magnet. When gas is 50 introduced through conduit 38 and valve 48 to the diaphragm chamber 58, this gas flows into bulb 60 and, as the pressure increases, causes the bulb to expand until it strikes the plates 61 and 62.

55 Inasmuch as the position of the latter plate may be adjusted by means of a set screw 63, the volume of gas which the bulb is able to accommodate may be regulated. After the bulb has been fully expanded against the plates, the introduction of further gas causes the pressure in the diaphragm chamber to increase and hence to exert a force against the diaphragm tending to move it to the left, as viewed in Fig. 1, which in turn tends to pivot member 46 in a counterclockwise direction. This is resisted by the attraction of the pole 53 of the magnet for the member 46 and when the pressure increases sufficiently to overcome this attraction the member 46 is suddenly pivoted to the position shown in Fig. 1, that 65 is with valve 48 closed and valve 49 open and member 46 in contact with the pole 52 of the magnet. The pressure within the diaphragm chamber 58 is that determined by the pressure regulator 14, for instance 5 mm. of water. This pressure consequently tends to open valve 55.

However, the loading of this valve is such that a higher pressure, of for instance 10 mm. of water is required to open it. Consequently, no gas passes through the valve. However, should the patient desire to be supplied with anesthetic she places the mask 58 over her mouth and nose and inhales. This reduces the pressure within the space 56 sufficiently so that valve 55 is opened and thus permits the anesthetic to flow through the space 56, tube 57 and mask 58 to the patient. The patient is able to inhale anesthetic until sufficient gas has been removed from the diaphragm chamber 58 and the bulb 60 to reduce the pressure in the diaphragm chamber slightly below atmospheric whereupon atmospheric pressure acting on the left side of the diaphragm moves it and the member 46 to a position in which valve 49 is closed and valve 48 is open. Thereafter, if the patient continues to inhale through the mask 58, the valve 55 is opened and she is supplied with atmospheric air.

The patient is not able to obtain further anesthetic immediately, but must wait until the diaphragm chamber 58 and bulb 60 has been filled again. The time required for filling is determined by the flow through the throttle valve 36, which hence may be set by the physician so as to determine the minimum time between periods when anesthetic is available. However, the patient herself controls when, after the minimum time has expired, the next period of supply is to occur. The physician is also able to regulate the quantity of anesthetic which the patient receives each time by adjusting the set screw 63 which regulates the volume of bulb 60 when fully expanded.

In the event that it becomes necessary to administer large quantities of anesthetic as in an emergency, this may be done by the physician or nurse depressing the button 34 which opens 41 valve 38 and permits gas to flow directly from the conduit 12 to the valve chamber 40, thus bypassing the pressure regulator 14 and the throttle valve 36 and hence supplying gas continuously to the valve chamber 40.

In the embodiment shown in Fig. 2, the container 18 is connected by means of conduit 12 with a pressure regulator 10. This regulator is similar to regulator 14 shown in Fig. 1, with the exception that the valve 38 establishes communication between the interior of the regulator casing and the conduit 32, instead of between the conduit 12 and conduit 32. In other words, valve 38 merely bypasses the throttle valve 36 and not both the throttle valve and the valve of the pressure regulator.

Conduit 38 leading from the throttle valve 36 communicates with a conduit 71, one end of which is connected to an expandible bulb 72, while the other end communicates with a valve chamber 73. Expansion of the bulb 72 is limited by means of plates 74 and 75. The former is adjustable by means of a set-screw 76 while the latter is mounted on an arm 77 pivoted at 78 and which carries an adjustable counter-weight 88. Movement of the arm 77 in a clockwise direction is limited by means of a fixed member 79. The opposite end of arm 77 is formed as an electric contact 80 which cooperates with a fixed contact 81.

A valve 82 controls communication between valve chamber 73 and the space 56 to which is connected the tube 57. Valve 82 is mounted on a valve stem 83 which extends outside the valve chamber 73 and is provided with an armature 84 75

of an electro-magnet 85. Valve 82 is loaded in any suitable manner, as by a spring, so that a certain pressure differential is required to open it. A loaded valve 59 is provided for establishing communication between space 56 and the atmosphere, as was the case in Fig. 1.

Pivoted arm 77 which carries contact 80 is connected by means of an electric conductor 86 with a suitable source of electric current, such as battery 87. The other terminal of the battery is connected by means of a conductor 88 with one terminal of electro-magnet 85, a variable resistance 89 being connected in series in the circuit. The other terminal of the electro-magnet 10 is connected by means of a conductor 90 with the contact 81. A large capacity condenser 91 is connected between conductors 88 and 90. A circuit 92 is connected across the terminals of the electro-magnet and includes a fixed contact 93 and a pivoted arm 94, the latter being movable with the button 34 of the valve 30 so as to close the circuit 92 and thus short-circuit the electro-magnet.

The above described apparatus operates as follows:

Gas under pressure is supplied from the container 10 to the conduit 12 to the pressure regulator 10, which is adjusted to maintain a pressure as for instance 5 mm. of water. The gas 30 flows from the regulator through throttle valve 36 and conduit 39 to conduit 71. The bulb 72 being deflated, the weight 69 maintains the arm 77 in a position with the contacts 80 and 81 closed. The circuit including the battery 87 and the electro-magnet 85 is thereby closed and the magnet is energized, thus attracting the armature 84 and holding valve 82 closed. At the same time the condenser 91 is charged. As the gas enters bulb 72 and causes it to expand, arm 40 77 is pivoted so as to break the circuit through contacts 80 and 81. However, the electro-magnet is maintained energized by means of the discharge from the condenser 91 and the length of time required for the condenser to be discharged 45 may be determined by the variable resistance 89. After this period of time has expired and the magnet de-energized, the valve 82 may be opened by the patient inhaling through the mask 58, which serves to reduce the pressure acting 50 on the upper side of the valve sufficiently so that, in conjunction with the gas pressure acting on the lower side of the valve, the latter opens against the force of the spring or other loading means. Thereafter, the patient may inhale 55 anesthetic until the supply contained in the bulb 72 has been depleted to such an extent that, due to collapse of the bulb, the contacts 80 and 81 are again closed. Throttle valve 36 restricts the flow of gas to conduit 71 to such an extent that 60 the patient exhausts gas from the bulb 72 faster than it is supplied through valve 36. The closing of contacts 80 and 81 causes the electro-magnet to be energized and to close the valve 82. Thereafter if the patient continues to inhale 65 through the mask she obtains fresh air through the valve 59, in the same manner as described in connection with Fig. 1.

In this embodiment the volume of the gas which the patient may obtain at any one time 70 may be predetermined by the setting of the set screw 16, which determines the maximum volume of the bulb 72. The minimum lapse of time required between administrations of the anesthetic may be determined by the setting of the 75 variable resistance 89, as this determines the

minimum length of time which the valve 82 remains closed under the influence of the electro-magnet.

In the event the physician desires to administer large quantities of anesthetic the button 34 is 5 depressed, which causes gas to be admitted to the conduit 71 at a faster rate inasmuch as throttle valve 36 is by-passed. Also, depression of the button 34 closes the circuit 92 and thus short-circuits the electro-magnet, thereby rendering it 10 ineffective to maintain the valve 82 closed, regardless of whether or not contacts 80 and 81 are closed.

In the embodiment shown in Fig. 3, the container 10 is connected by means of a conduit 12 15 with a pressure regulator 14, of the type shown in Fig. 1. Conduit 28 connects the outlet of the pressure regulator with throttle valve 36 and conduit 39 connects the throttle valve with the valve chamber 40 formed within casing 41. 20

The diaphragm 42 is mounted within casing 41 and is connected by means of arm 45 with the member 46 which is pivoted at 47 to the casing 41. Member 46 carries valves 48 and 49 adjacent to one end and has its other end disposed 25 between the poles 52 and 53 of the permanent magnet 54.

An electro-magnet 95 is arranged so as to magnetically attract member 46. Magnet 95 includes an energizing winding 96 and a short-circuited winding 97. One terminal of the winding 96 is connected to a fixed contact 98 which cooperates with a pivoted switch arm 99 arranged in magnetic relation to the electro-magnet so as to be moved away from contact 30 99, against the action of a spring 100, under the magnet effect of the electro-magnet. Switch arm 99 is connected by means of a conductor 101 with one terminal of a battery 102. The other terminal of the battery is connected by means 40 of a conductor 103 with a pivoted arm 104 which carries a contact 105 at one end. The other end of arm 104 is connected by means of a link 106 with the diaphragm 42. Contact 105 cooperates with a fixed contact 107 which is connected by 45 means of a conductor 108 with the other terminal of the winding 96, a variable resistance 109 being interposed in conductor 108. A condenser 110 of large capacity is connected across the terminals of the winding 96 and in series with 50 the resistance 109.

The diaphragm chamber 50 is connected to a rubber bulb 111, or the like, expansion of which in this embodiment is not restrained by means of fixed or adjustable plates. Communication 55 between chamber 51 and space 56 is controlled by the loaded valve 55, which is similar to the valve 55 shown in Fig. 1. Space 56 is connected by means of a tube 57 with the inhalation mask 58. The loaded valve 59 controls communication 60 between space 56 and the atmosphere.

The operation of the above described device is as follows:

When the apparatus is first started the member 46 is in the opposite position from that shown 65 in Fig. 3, namely, with the valve 48 opened and the valve 49 closed and the opposite end of the member in contact with the pole 53 of the permanent magnet 54. Also, contacts 105 and 107 are closed due to the position of diaphragm 42 70 and contacts 98 and 99 are also closed, due to the fact that the electro-magnet 95 has not been energized. Consequently, the circuit to the magnet is closed and the winding 96 is supplied with current. However, the short-circuited winding 97 75

delays the energization of the electro-magnet a sufficient length of time to permit the condenser 110 to be charged. When the electro-magnet is fully energized, it attracts switch arm 88 away from contact 88, thus opening the battery circuit. However, the electro-magnet remains energized due to the discharge from the condenser 110, and consequently continues to attract the member 46.

10 In the meantime gas is being supplied through conduit 12, pressure regulator 14, conduit 28, throttle valve 36 and conduit 38 to the valve chamber 40. The valve 48 being open, the gas passes into diaphragm chamber 58 and into bulb 15 111.

After a predetermined period of time, which may be regulated by the setting of the variable resistance 109, the condenser 110 becomes discharged and hence electro-magnet 88 becomes de-energized. When this happens the pressure acting on diaphragm 42 causes the latter to move to the left, as viewed in Fig. 3, thereby closing valve 48 and opening valve 49, and also opening contacts 105 and 107. Upon the de-energization of the electro-magnet, the contacts 88 and 99 are closed under the influence of spring 100, but the electro-magnet circuit remains open due to the open contacts 105 and 107.

The pressure regulator 14 is set to maintain a pressure which is slightly lower than that required to open valve 55. However, as soon as the patient inhales through the mask 58, this reduces the pressure in the space 56 sufficiently so that valve 55 is opened and gas passes therefrom to the mask. Flow of gas in this manner continues until the pressure has been reduced sufficiently in the diaphragm chamber to cause diaphragm 42 to move member 46 so as to close valve 49 and open valve 48. This movement of 40 the diaphragm also closes contacts 105 and 107 and the apparatus is in condition to repeat the above described cycle.

In this embodiment, as was the case in Fig. 1, the minimum length of time between the periods 45 in which the apparatus is capable of supplying gas to the mask is determined by the rate of flow through the throttle valve 36, and this may be adjusted by the physician. In this embodiment the volume of gas available is determined by the 50 setting of the variable resistance 109, inasmuch as this determines the length of time which the electro-magnet is energized, and hence the length of time which the valve 48 is open. Obviously the longer this valve is open the more gas will 55 flow into the expandable bulb 111. Inasmuch as expansion of the bulb is not restrained by fixed or adjustable plates, the volume of gas which will flow thereinto, at least within the limits of elasticity of the material of the bulb, is determined by the length of time during which flow is 60 permitted, which, as above described, is regulated by the setting of the variable resistance 109.

If, in an emergency, the physician wishes to administer larger amounts of anesthetic, this 65 may be done by depressing button 34, thus opening valve 38 and permitting gas to flow directly from conduit 12 to the valve chamber 40, as was the case in Fig. 1.

It will thus be seen that in each of the three 70 embodiments, herein disclosed by way of example, the apparatus may be set by a physician or other skilled person so as to be capable of supplying a predetermined maximum amount of gas periodically, and the minimum time between periods 75 may be similarly regulated. However, the

patient herself determines the length of time, above this minimum, between the periods.

While I have shown several embodiments of my invention this has been done for purposes of illustration only, and is not to be considered as limiting the scope of my invention.

What I claim is:

1. In an apparatus for administering a gaseous anesthetic to a patient, an expandible chamber, means for supplying gas to said chamber, an inhalation mask, conduit means for conveying gas from said chamber to said mask, and means automatically operating independently of the action of the patient for interrupting the supply of gas to said mask for a predetermined and appreciable minimum length of time whenever the expandible chamber is emptied of gas.

2. In an apparatus for administering a gaseous anesthetic to a patient, an expandible chamber, means for supplying gas to said chamber, means for automatically interrupting the flow of gas to said chamber when a predetermined amount has been supplied, an inhalation mask, conduit means for conveying gas from said chamber to said mask, and means automatically operating independently of the action of the patient for interrupting the supply of gas to said mask for an appreciable minimum length of time whenever the expandible chamber is emptied of gas.

3. In an apparatus for administering a gaseous anesthetic, an expandible chamber, means for supplying gas to said chamber, an inhalation mask, a conduit for conveying gas from said chamber to said mask, a first valve in said conduit, means for maintaining said valve closed for a predetermined length of time after said chamber has been emptied, and a second valve in said conduit operable under the control of the patient.

4. In an apparatus for administering a gaseous anesthetic, an expandible chamber, means for supplying gas to said chamber, an inhalation mask, a conduit for conveying gas from said chamber to said mask, a first valve in said conduit, means for maintaining said valve closed for a predetermined length of time after said chamber has been emptied, a second valve in said conduit operable under control of the patient whenever said first valve is open, and a valve connecting said conduit with the atmosphere and operable under control of the patient whenever said first valve is closed.

5. In an apparatus for administering a gaseous anesthetic, an expandible chamber, means for supplying gas to said chamber at an adjustable rate and under a predetermined pressure, an inhalation mask, a conduit for conveying gas from said chamber to said mask, a first valve in said conduit, means for opening said valve when said pressure is attained in said chamber, a second valve in said conduit, means for loading said second valve so that it remains closed under said pressure and opens under the increased pressure differential resulting from the patient inhaling through said mask, a valve connecting said conduit with the atmosphere, and means for loading the last mentioned valve so that a greater pressure differential is required to open it than is required to open said second valve.

6. In an apparatus for administering a gaseous anesthetic, an expandible chamber, a conduit for supplying gas to said chamber, means for regulating the rate of flow of gas through said conduit, an inhalation mask, conduit means for

conveying gas from said chamber to said mask, and means responsive to the rate of flow of gas through said first mentioned conduit for interrupting the supply of gas to said mask for a minimum length of time.

7. In an apparatus for administering a gaseous anesthetic, an expansible chamber, means for supplying gas to said chamber, an inhalation mask, conduit means for conveying gas from said chamber to said mask, a diaphragm subjected to the pressure of the gas in said chamber, a valve for controlling the supply of gas to said chamber operable by said diaphragm so as to be closed upon an increase in pressure, a valve for controlling the flow of gas from said chamber to said mask operable by said diaphragm so as to be closed upon a decrease in pressure, and means for regulating the rate at which gas is supplied to said chamber when the first mentioned valve is open to thereby determine the length of time the second mentioned valve is maintained closed.

8. In an apparatus for administering a gaseous anesthetic, an expansible chamber, means for supplying gas to said chamber, an inhalation mask, a conduit for conducting gas from said chamber to said mask, a valve in said conduit, and means for maintaining said valve closed when said chamber is deflated and for a minimum length of time after said chamber is expanded.

9. In an apparatus for administering a gaseous anesthetic, an expansible chamber, means for supplying gas to said chamber under a predetermined pressure, an inhalation mask, a conduit for conducting gas from said chamber to said mask, a valve in said conduit, means for maintaining said valve closed when said chamber is deflated and for a minimum length of time after said chamber is expanded, and means for permanently applying a force to said valve tending to maintain it closed, said force being greater than the force exerted on the valve by the gas under said pressure and less than the force exerted on the valve caused by the pressure differential resulting from the patient inhaling through said mask.

10. In an apparatus for administering a gaseous anesthetic, an expansible chamber, means for supplying gas to said chamber, an inhalation mask, a conduit for conducting gas from said

chamber to said mask, a valve in said conduit, an electro-magnet for maintaining said valve closed, means for energizing said electro-magnet when said chamber is deflated, and an electric condenser for maintaining said electro-magnet energized for a predetermined length of time after said chamber is expanded. 5

11. In an apparatus for administering a gaseous anesthetic, an expansible chamber, a conduit for supplying gas to said chamber, an adjustable throttle valve for regulating the rate of flow of gas through said conduit, an inhalation mask, conduit means for conveying gas from said chamber to said mask, means responsive to the rate of flow of gas through said first mentioned conduit for interrupting the supply of gas to said mask for a minimum length of time, and means for by-passing said throttle valve to supply gas at an increased rate to said chamber. 15

12. In an apparatus for administering a gaseous anesthetic, an expansible chamber, a conduit for supplying gas to said chamber, an adjustable throttle valve in said conduit, an inhalation mask, a conduit for conducting gas from said chamber to said mask, a valve in the last mentioned conduit, means for maintaining the last mentioned valve closed when said chamber is deflated and for a minimum length of time after said chamber is expanded, and means for by-passing said throttle valve and for rendering 30 the last mentioned means inoperative, whereby an increased quantity of gas is supplied continuously to said mask. 20

13. In an apparatus for administering a gaseous anesthetic, an expansible chamber, a conduit for supplying gas to said chamber, an adjustable throttle valve in said conduit, an inhalation mask, a conduit for conducting gas from said chamber to said mask, a valve in the last mentioned conduit, an electro-magnet for maintaining the last mentioned valve closed, means for energizing said electro-magnet when said chamber is deflated, an electric condenser for maintaining said electro-magnet energized for a predetermined length of time after said chamber is expanded, and means for by-passing said throttle valve and for maintaining said electro-magnet deenergized, whereby an increased quantity of gas is supplied continuously to said mask. 45

EMIL EINAR WILHELM ANDERSON. 50
